UNITED STATES PATENT OFFICE.

CHARLES W. SCHLEIER, OF WELLSTON, MISSOURI.

COMBINED HAT-ORNAMENT BAND AND HAT-PIN-POINT PROTECTOR.

1,034,310.

Specification of Letters Patent. Patented July 30, 1912.

Application filed March 27, 1911. Serial No. 617,041.

To all whom it may concern.

Be it known that I, CHARLES W. SCHLEIER, a citizen of the United States, residing at Wellston, in the county of St. Louis and State of Missouri, have invented new and useful Improvements in Combined Hat-Ornament Bands and Hat-Pin-Point Protectors, of which the following is a specification.

10 This invention relates to a combined hat ornament and hat pin point protector, and the primary object of the invention is to provide a device of this character which is of an extremely simple construction, which 15 may be readily applied to a lady's hat, or which may remain a permanent part thereof and which not only adds to the ornamentality of the hat but also protects the point of a hat pin, so as to effectively overcome 20 the dangers of the projecting pins, when the hat is worn on public thoroughfares.

Another object of the invention is the provision, in a device of this character, of means whereby the hat pin is secured both 25 adjacent its head and its point, the securing device for the point comprising a shield which effectively protects the said point.

A still further object of the invention is to provide a device of this character which 30 secures both the point and the head of the pin, the said device adapted to exert a sufficient amount of pressure between the head and the pin to prevent the accidental removal of the said device from the pin.

35 With the above objects in view, and others which will appear as the nature of the invention progresses, the improvement resides in the novel construction and arrangement of parts hereinafter fully described 40 and claimed.

In the drawings, accompanying this specification, there has been illustrated a simple and preferred embodiment of the improvement, it being understood, however, 45 that the showing therein is merely illustrative, and that minor details, such as size, proportion, material, etc., which fall within the scope of the appended claims, may be resorted to if desired.

50 In the drawings—Figure 1 is a perspective view illustrating my device in applied position upon a lady's hat. Fig. 2 is a top plan view of the same removed from the hat. Fig. 3 is a similar view, parts being 55 shown in section, and illustrating the hat pin swung free of its shield or pocket. Fig.

4 is a top plan view of the improvement, the hat pin being illustrated as a separate member. Fig. 5 is a detail plan view illustrating a slightly modified form of the point receiving shield or pocket. Fig. 6 is a similar view illustrating a still further form of the shield or pocket.

It is a well known fact that the projecting points of pins inserted in ladies' hats has become a great source of danger and a menace to the public, especially when the hat is worn on crowded thoroughfares, street cars, public places, such as churches, assemblies, theaters, etc. The projecting pins are also 60 a source of danger even when the hat is removed from the head of the wearer, as will be readily understood, and it is the primary object of the present invention to provide a simple and effective device which not only 65 overcomes the above named objections, but which also adds greatly to the ornamentation of the hat. To accomplish this purpose, I have provided a device comprising 70 essentially a band 1 which may be constructed of any desired material having sufficient resiliency to normally force its ends one toward the other. One end of the band is provided with a hinged member 2, while the opposite end of the band is bent upon itself to 75 form a pocket or shield 3. The inner wall of the said pocket 3 is provided with an opening 4, the latter adapted to serve as a means whereby the pointed end of a hat pin 80 body may be positioned within the pocket or 85 shield. The band 1 may be suitably ornamental, and the pocket or shield 3 may be likewise formed with an ornamental head, as illustrated in Figs. 5 and 6 of the drawings. The pin 5 may have its headed portion secured to the hinge 2 as illustrated in 90 Figs. 1, 2 and 3 of the drawings, or the hinge 2 may be provided with a suitable opening through which the pin 5 may be 95 inserted and the head 6 thereof brought into 100 contact with the hinge 2.

It is to be understood that the band 1 may be secured to the hat if desired, but in most instances it has been found desirable to have the band as a separate element from the hat. 105 In positioning the device upon a hat, the pin 5 is first inserted through the hat and through the hair of the wearer of the hat. The yieldable band is then swung around the hat until the opening 4 of the shield or 110 protector 3 is brought to register with the point of the pin when the said shield,

through the flexibility of the band 1 will automatically position itself upon the point of the pin.

In the device illustrated in Fig. 4 of the drawings, the pin 5 is first inserted through the opening in the hinge 2 of the device. The pin is then inserted through the hat then through the hair of the wearer of the hat, then the band is brought around the hat so that the point of the pin is received in the shield or protector 3.

In Fig. 5 I have illustrated the shield or protector as a substantially rectangular element, and whereby a suitable ornamented head 14 having its back flattened may be attached to the flattened outer face of the shield or protector 15.

In Fig. 6 the shield or protector 16 has its outer face rounded, whereby a cone or hollow ornamental head 17 may be snugly positioned thereon and secured thereto.

It is to be understood that the hat pins as well as the band may be of any desired size to accommodate themselves to the various sizes of hats according to the changing styles, and in order to more effectively sustain the pin within the pocket of the device I have formed the inner face of the said pocket, adjacent the outer edge thereof, with the curved hooks 18, the same adapted to enter the hat after the shield or protector has engaged with the pin.

From the above description, taken in connection with the accompanying drawings, the simplicity of the device, as well as the advantages thereof, will, it is thought, commend themselves to those skilled in the art to which such inventions appertain, and it is thought that the above description taken

in connection with the drawings will fully set forth the details of my structure.

Having thus fully described the said invention, what I claim is:—

1. A hat band and pin point protector comprising an elastic band of flattened material, the said band having one of its ends provided with a hinged member, the said hinged member having an opening for the reception of the hat pin, the opposite end of the band being bent upon itself to provide a pocket, the inner wall of the said pocket having an opening through which the end of the hat pin is adapted to pass into the pocket, and the said pocket having one of its edges provided with a hook adapted to engage with the hat.

2. A device for the purpose set forth comprising a flattened elastic band of an arcuate formation, the said band having one of its ends provided with a hinged portion, said hinged member having an opening, the opposite end of the band being bent to provide an inwardly extending angular portion, provided with a hook and having a wall connecting the said angular portion with the band, the said wall being provided with an opening, the opening of the wall as well as the opening of the hinged member adapted to receive the hat pin, and the hook of the wall adapted to be inserted into the hat.

In testimony whereof I affix my signature in presence of two witnesses.

CHARLES W. SCHLEIER.
